UNITED STATES PATENT OFFICE.

EDMUND R. WEEK, OF SPOKANE, WASHINGTON.

CENTRIFUGAL ORE-CONCENTRATOR.

SPECIFICATION forming part of Letters Patent No. 757,699, dated April 19, 1904.

Application filed October 22, 1903. Serial No. 178,132. (No model.)

To all whom it may concern:

Be it known that I, EDMUND R. WEEK, a citizen of the United States, residing at Spokane, in the county of Spokane and State of Washington, have invented new and useful Improvements in Centrifugal Ore-Concentrators, of which the following is a specification.

This invention relates to centrifugal ore concentrators and amalgamators.

With the present methods of milling gold and other precious metal bearing ores a large part of the gold and concentrates is carried off or entrained in a very finely divided state in approximately clear water, and large losses are thereby sustained.

The object of the present invention is the provision of an improved centrifugal concentrator and amalgamator adapted to treat the water containing these entrained finely-divided particles of gold and other precious metals and reclaim them; and with this end in view the invention consists of a centrifugal concentrator and amalgamator of improved construction adapted to extract the fine particles of gold and other precious metal in a novel manner, which is of simple and inexpensive construction and durable and reliable in action.

The invention embraces those improved features and novel combinations of elements set forth in detail hereinafter and recited in the appended claims.

In the accompanying drawings, Figure 1 is a vertical section of the machine, taken on line 1 1 of Fig. 3, showing one of the blades in dotted lines and one in section; Fig. 2, a cross-section on line 2 2 of Fig. 1, and Fig. 3 a cross-section on line 3 3 of Fig. 1.

The machine has a base 1, of circular shape, provided with an annular trough or recess 2, adapted to contain mercury 3, (shown by a dotted line in Fig. 1,) depending centrally from the base in a hub 4, having discharge ports or passages 5. A cone 6, having an inlet-opening 7, is screwed to the base at 8, and a shoulder 9 is provided to form a proper seat for the cone. Within the outer cone 6 is another cone 10, which has blades 11. Any number of these blades may be employed. The inner cone is preferably connected to the outer cone

through the medium of the blades. Screwed into the base of the inner cone is a shaft 12, which passes through the hub 4 and is keyed thereto at 13, said shaft being provided with any suitable driving means, and it has a cone 55 14, seated on balls 15 in a suitable support 16. A suitable box or hopper 17 is secured to the support 16 and fits sufficiently tight around the hub 4 so that the water passing down through the opening 5 will enter said box 17 60 and be prevented from splashing and will then pass out through the opening 18 in the bottom of the box.

In operation the shaft 12 is revolved at, say, one thousand revolutions or upward per minute, and the cones 6 and 10 turn with said shaft, the ball-bearings 14 15 minimizing friction and rendering the operation easy. The water, with entrained finely-divided particles of gold or other precious metal taken from 70 the concentrating-table, is introduced through the opening 7 and whirled around between and with the cones by the blades 11 and passes down into the base 1 and out through the passages 5 into the box 17 and thence through 75 discharge 18 to any suitable point. The centrifugal action throws the metal particles, which are heavier than the water, outwardly against the cone 6, and they then pass down the inner surface of said cone into the mercury 3, which amalgamates them. The centrifugal action keeps the mercury and amalgamated particles in the position indicated in Fig. 1 while the machine is in operation, and when the machine is stopped the mercury and particles amalgamated therewith drop into the bottom of the trough or recess 2, and when it is considered that a sufficient quantity has been amalgamated the cone 3 can be unscrewed 80 and the mercury and amalgamated particles removed and fresh mercury placed in trough or recess 2. The cone 10, with its wings or blades, insures the subjection of all of the water introduced to a large amount of centrifugal action, and the separation of the particles, 85 no matter how finely divided, is satisfactorily accomplished by the operation of the machine, which saves the large amounts of precious metal usually lost by entraining off the water from concentrating-tables.

Having thus described my invention, what I claim as new, and desire to secure by Letters Patent, is—

1. A centrifugal ore concentrator and amalgamator, comprising a rotatable base having water-escape openings and an annular trough, an outer cone having its lower edge concentric with the trough, and provided with an inlet-opening in its upper end, an inner concentric cone supported above said base, and one or more radial wings extending across the annular space between said cones.

2. A centrifugal ore concentrator and amalgamator, comprising a rotatable base provided with a peripheral trough and having a hub containing water-escape openings, a cone having its lower edge coincident with the outer wall of the trough and provided with an inlet

in its upper end, and an inner concentric cone supported above said base.

3. A centrifugal ore concentrator and amalgamator, comprising two concentric cones affording between them an annular space increasing in diameter from above downward, a mercury-trough below and concentric with said space, means for rotating said cones and trough, and openings in the bottom of said outer cone for the escape of material fed to the machine.

In testimony whereof I have signed my name to this specification in the presence of two subscribing witnesses.

EDMUND R. WEEK.
